UNITED STATES PATENT OFFICE.

CHALMER C. MENESEE AND ELMER MENESEE, OF GILBERT, OHIO; SAID ELMER MENESEE ASSIGNOR OF ONE-EIGHTH TO JAMES H. ANDERSON, OF ZANESVILLE, OHIO.

AMUSEMENT DEVICE.

Application filed April 26, 1923. Serial No. 634,788.

To all whom it may concern:

Be it known that we, CHALMER C. MENESEE and ELMER MENESEE, citizens of the United States, residing at Gilbert, in the county of 3 Muskingum and State of Ohio, have invented certain new and useful Improvements in an Amusement Device, of which the following is a specification.

The present invention relates to an amusement device particularly designed for youngsters having for its object to provide devices which may be attached to their shoes and upon which they may jump and run with a springing movement, causing them considerable amusement and exercise of a helpful nature.

Another important object of the invention is to provide a device of this nature having a durable structure which is comparatively 20 simple and may be manufactured at a low cost.

With the above and numerous other objects in view as will appear as the description progresses, the invention resides in certain 25 novel features of construction and in the combination and arrangement of parts as will be hereinafter more fully described and claimed.

In the drawing—

Figure 1 is a perspective showing the devices on the shoes of a youngster,

Figure 2 is a side elevation of one of the devices,

Figure 3 is a horizontal section taken substantially on the line 3—3 of Figure 2 looking in the direction of the arrow,

Figure 4 is a detail perspective of one end of the bottom plate showing a spring attached thereto, and

Figure 5 is a perspective view of one of the devices showing the parts thereof disassembled.

Referring to the drawing in detail it will be seen that the devices are two in number one for each shoe. Each device may be used upon either shoe and the devices are, therefore, interchangeable. The numeral 1 indicates the bottom plate upon which is mounted a plurality of coil springs 2 which are preferably three in number. These coil 50 springs 2 are held in engagement with the bottom plate 1 by a strap iron 3 which engages the lower convolutions of the springs and is riveted or otherwise fixedly attached to the plate 1. A top plate 4 is mounted on the springs 2 and a strap iron 5 secures the top

convolutions of these springs to the under surface of the plate 4, this strap iron being riveted or otherwise fixedly attached to the plate.

A foot engaging plate 7 consists of a heel section 8 and a toe section 9. The heel section 8 is provided with the extension 10 at its forward end which is adapted to overlie an extension 11 projecting from the rear end of the toe plate. The projection 10 extends into a slot 12 so as to partially underlie the toe plate as is seen to advantage in Figure 2.

The extension 11 is provided with a slot 13 at its end adapted to register with an aperture 14 in the heel plate 8 so that a bolt 15 may penetrate the aperture and the slot for holding the sections in adjusted positions whereby the length of the shoe plate may be varied. It will be noted that this plate is 75 very similar to that commonly used upon roller skates. This plate 7 may be attached to the shoe by means of suitable straps 16 and 17. The strap 17 preferably engages the heel flange 18 provided on the heel section 8 of the 60 plate 7 while the strap 16 engages under the plate 4 and round the toe portion of the shoe.

This shoe plate 7 is mounted on top of the top plate 4 being held in engagement therewith by screws 19 or any other suitable means. 65 It is preferable to construct the top plate 4 of wood so that these screws 19 may engage any portion thereof after the shoe plate 7 has been adjusted to the desired length.

When the devices are secured to the shoes 90 of a youngster he may jump about or run and the springs 2 will aid him in jumping and afford him considerable exercise and amusement. The device is very durable and will stand considerable abuse and last for a long 95 time without any attention being given thereto.

We have, in the present instance, shown and described the preferred embodiment of the invention which will give in practice satisfactory and reliable results, and it is to be understood that the same is susceptible of modification in various particulars without departing from the spirit or scope of the invention or sacrificing any of its advantages. 100

Having thus described our invention what we claim as new is:—

1. A device of the class described including an upper plate, a lower plate, a spring disposed between the plates, a strap iron se- 110

cured to each plate for securing the adjacent convolutions of the spring thereto, and an adjustable shoe plate mounted on the upper plate and secured thereto.

5 2. A device of the class described including an upper plate, a lower plate, a plurality of coil springs disposed between the plates, straps irons secured to the plates and passing over the end convolutions of the springs so 10 as to fix said convolutions to the plates, and

an adjustable shoe plate mounted on the upper plate and secured thereto.

In testimony whereof we affix our signatures in presence of two witnesses.

CHALMER C. MENESEE.
ELMER MENESEE.
